UNITED STATES PATENT OFFICE.

HAROLD C. PYE, OF OAK PARK, ILLINOIS, ASSIGNOR TO AUTOMATIC ELECTRIC INC.,
OF CHICAGO, ILLINOIS, A CORPORATION OF DELAWARE.

TELEPHONE TRANSMITTER.

Application filed December 10, 1925. Serial No. 74,453.

This invention relates in general to telephone transmitters, more particularly to transmitters in which the microphone element is of the granular carbon type, and has 5 for its principal object the development of a transmitter whose microphone cell will not open circuit or materially change in resistance regardless of the position in which the transmitter is used.

10 A further object of my invention is to provide a microphone cell of rugged construction without impairing its efficiency.

Further objects of my invention will be apparent from the detailed description and 15 claims which follow.

Transmitters used on desk telephones and cradle type telephone, more particularly on the latter type, are apt to be used in any position. That is, some people using the cradle 20 type telephone will hold the instrument in such a position that the main diaphragm of the transmitter is horizontal with the microphone cell beneath the diaphragm, that is, the transmitter will be on its back. Other people 25 may hold the instrument in such a position that the microphone cell will be above the horizontal diaphragm, or, in other words, the transmitter will be on its face.

In the well known common battery type of 30 telephone systems, either manually operated or automatically operated, the circuit of a holding relay at the exchange extends through the transmitter at the substation and if this circuit is open the manual disconnect 35 signal will be lighted, or the automatic switch train will be automatically released. In the present well known type of transmitter having parallel electrodes in the microphone cell, there is a strong probability that the trans- 40 mitter will open circuit if it is laid on its face or on its back, or if the transmitter does not open circuit, it will increase in resistance sufficiently to allow this holding relay to restore with the above mentioned result. Also the 45 transmitter of the well known type, because of this increased resistance, is decidedly less efficient as a transmitting medium when it is operated with its electrodes in a horizontal position. It is for the correcting of these few 50 very serious faults that I have designed a transmitter built in accordance with the object of this invention for use on a cradle type telephone.

The drawings comprising Figs. 1, 2, 3 and 4 55 show the details of a transmitter constructed

in accordance with the object of my invention. Figure 1 is a detailed cross section view of a completely assembled transmitter shown in enlarged scale to permit a clear showing of the details. Figure 2 is a back view of the 60 assembled transmitter showing particularly the back terminal mounting and insulation. Figure 3 is a detailed view of the face of the back electrodes comprising electrode members 5 and 7 separated by the insulating member 10. Fig. 4 shows the details of the connections between the electrodes and terminal strips.

Referring now to Fig. 1 in more detail, it will be noted that I have assembled my transmitter in a standard front piece 1 and on a standard back bridge plate 2, these members not forming an essential part of the invention. The microphone cell comprises the brass cup 3 into which I have mounted the 75 electrodes 5, 6, 7, and 8. The cell is completely lined with the insulating material 9, which may be of paper or any other suitable insulating material.

The microphone cell is fastened to the back 80 bridge 2 by means of the back electrodes 5 and 6, which extend through the cup, bridge and terminals, being insulated from the cup and bridge by means of the bushings 18 and 19, and attached to the terminals 12 and 13 85 by means of the nuts 12' and 13'. The microphone cell cup 3 is further insulated from the back ring by the insulating washer 17, and the terminals 12 and 13 are insulated from this ring by means of the common in- 90 sulating member 18.

The front electrodes 6 and 8 are mounted on the mica diaphragm 22, which closes the granular carbon chamber, by means of the mounting member 14 from which the elec- 95 trodes are insulated by the bushings 20 and 21 and the insulating washer 24. Projecting from this mounting member 14 is the screw 14' by means of which the front electrode assembly is attached to the main diaphragm 100 4 by the lock nuts 15. This front electrode assembly comprising the mica diaphragm and electrodes is held on to the brass cup by means of the clamping ring 23, which may be either pressed on to the cup 3, or screwed on. I 105 have placed a paper ring 23' between the clamping ring 23 and the mica diaphragm 22, to protect the latter from injury as the former is being placed.

The main diaphragm is insulated from the 110

front piece by the insulating ring 16, completing the transmitter insulation, so that all electrical circuits are insulated from the frame to prevent the possibility of a person receiving a shock when using the transmitter.

Referring now to the electrodes, the back electrodes 5 and 7 are semi circular in shape and are separated from each other by means 10 of the insulating strip 10 substantially as shown in Fig. 3. These electrodes comprise the usual polished carbon face electrodes, which are attached to the electrode stems 5' and 7' by means of which the electrodes are 15 attached to the microphone cell and back bridge as explained hereinbefore. The front electrodes 6 and 8 are constructed in a similar manner and are separated by the insulating members 11.

20 In connecting the four electrode members into the telephone circuit, I connect the back electrode 5 with the front electrode which is diagonally opposite, that is, the electrode 8, and in a similar manner connect the electrodes 6 and 7 together. By this arrangement I have secured a transmitter microphone cell which when filled with granular carbon or other suitable comminuted resistance material, will not open circuit or materially increase in resistance in any position that it might be placed. The cell should be filled so that the carbon covers all electrodes when the transmitter is placed as shown.

Assume for the moment that the transmitter is being used while it is lying on its back, 35 that is with the back electrodes 5 and 7 undermost. The supply of granular carbon in the microphone cell will then be resting squarely on these electrodes and will pile up touching parts of the front electrodes 6 and 8. The 40 main path for the current in this case will be from the terminal 12 through the back electrode 5, through the granular carbon, through the back electrode 7 and thence to the terminal 45 13 and out to the external circuit. The front electrode being vibrated by the main diaphragm in response to the voice waves directed against it, will alternately compress and rarefy this granular carbon to change its resistance and modulate the electrical current 50 in the well known manner. In this case the front electrodes 6 and 8 may carry some current as the granular carbon is also in contact with them, but the amount of this current and 55 its effect upon the external circuit is small.

In the event that the transmitter is being used face down, that is, with the front electrodes 6 and 8 undermost, the action is the same as that which has just been explained 60 except that the major path for the current will be from the electrode 6 to the electrode 8, and that the entire pile of carbon will be moved by the vibrating front electrode assembly with the back electrode assembly as a 65 stationary pusher.

With the transmitter used in the position shown in Fig. 1, the major path for the current is from the front electrode 8 to the back electrode 7, with a minor path through the electrodes 5 and 6.

With the transmitter in such a position that the insulating members 10 and 11 are vertical there are two parallel paths through the granular carbon, the one from the bottom part of electrodes 5 and 6 and the other from the 75 bottom part of electrodes 7 and 8, the granular carbon being agitated by the movable electrodes 6 and 8 as before.

Figure 2 shows the back view of the assembled transmitter disclosing a method I 80 employ to connect the diagonally opposite electrodes together. I have provided the terminal strips 12 and 13 which rest on the back bridge 2 and are insulated therefrom by means of the insulating strip 18. The screws of the back electrodes 5' and 7' extend through the back bridge and through these terminals being attached thereto by means of the nuts 12' and 13'. In order to connect the diagonally opposite front electrodes to the 85 terminal 12, I extend this terminal strip out and over the edge of the back bridge 2 bending it down so that the soldering strip of the terminal lies adjacent to the nut holding the front electrode 8 to the front mounting plate 90 14. I make a connection from this terminal to the nut by means of a flexible conductor. Similarly the terminal 13 is bent down and connected to the front electrode 6, thereby connecting the electrodes in pairs, 5 and 8, and 95 6 and 7.

Tests upon sample transmitters made substantially as shown in the foregoing description and drawings, show that the transmitters maintain a practically constant average resistance in all positions. In other words, these tests show that the spacing and size of the electrodes is such that the average resistance of the electrical path through the transmitter is the same, regardless of whether 105 that path is lateral between electrodes in the same plane or between electrodes in opposite planes. The tests also show a constant average resistance when the transmitter is placed so that the path through it is made up 110 of a combination of front to back paths and lateral paths.

From the foregoing specification it is apparent that I have designed a new and useful transmitter structure, which will not open 120 circuit or materially change its resistance with a change in position, and which, because of its nearly constant resistance, has equally good transmitting quantities in all positions. While I have chosen to show my invention in 125 connection with a particular type of transmitter, I have done so merely by way of example, as there are many modifications which can be made by one skilled in the art without departing from the scope of my invention. 130

Having thus described my invention what I consider new and desire to have protected by Letters Patent is pointed out in the appended claims.

5. What is claimed is:

1. In a telephone transmitter, a microphone cell having two back electrodes, said electrodes being insulated from said cell and from each other by suitable insulating members, a 10 mica diaphragm closing said cell, a front electrode assembly on said diaphragm, said assembly comprising two electrodes and a mounting member, said electrodes being insulated from said member and from each 15 other by suitable insulators, terminals for said transmitter, one of said terminals being connected to one back electrode and to the front electrode diagonally opposite, the other terminal being connected to the other back 20 electrode and to the front electrode diagonally opposite from it, granular carbon in said cell, and a path for current led into one of said terminals from an external circuit leading from the electrodes connected to that termi-

nal, through said granular carbon to the electrodes connected to the other said terminal.

2. In a telephone transmitter, a microphone cell, a plurality of rigidly mounted back electrodes, a plurality of movable front electrodes, comminuted resistance material in 30 said cell between said electrodes, means for connecting said electrodes in multiple to form a plurality of current paths through said resistance, some of said paths being between front and back electrodes and other paths 35 being lateral between members of said front or back electrodes, one or the other of said paths being the major path dependent upon the position of the transmitter, the electrodes being so proportioned and spaced that the 40 average resistance of said front and back major paths equals the average resistance of said lateral major paths.

In witness whereof, I hereunto subscribe my name this 4th day of December, A. D. 45 1925.

HAROLD C. PYE.
